UNITED STATES PATENT OFFICE.

BEN B. JOHNSTON, OF FORT SMITH, ARKANSAS, ASSIGNOR TO FORT SMITH BODY COMPANY, OF FORT SMITH, ARKANSAS.

FASTENER FOR STAKE GATES.

Application filed March 13, 1925. Serial No. 15,414.

To all whom it may concern:

Be it known that I, BEN B. JOHNSTON, a citizen of the United States, residing at Fort Smith, in the county of Sebastian and State of Arkansas, have invented certain new and useful Improvements in a Fastener for Stake Gates, of which the following is a specification.

The present invention relates to fasteners 10 for stake gates and has for its principal object to provide a fastener of this nature which will prevent the gates from jumping out of their sockets and strengthen the side and end gate construction.

15 Other important objects of the invention are to provide a device of this nature which will allow the gates to be easily lifted out of their sockets when desired, which will maintain the gates secure in place when desired, which will facilitate and provide for easily locking the stake gates in their proper places, and prevent them from being pushed out when two gates are locked together.

20 Another very important object of the invention is to provide a fastener of this nature which may be interchangeably used either on the side or end gates.

A still further very important object of 30 the invention is to provide a fastener of this nature which is simple in construction, efficient and reliable in use, inexpensive to manufacture, strong, durable, easy to manipulate, and otherwise well adapted to the purpose for which it is designed.

With the above and numerous other objects in view as will appear as the description proceeds, the invention resides in certain novel features of construction, and in 40 the combination and arrangement of parts as will be hereinafter more fully described and claimed.

In the drawing,

Figure 1 is a fragmentary elevation of a 45 stake gate structure showing one of my fasteners associated therewith,

Fig. 2 is a top plan view of the structure shown in Fig. 1,

Fig. 3 is an enlarged elevation of one 50 of the leaves showing a portion thereof in section with the links associated therewith also shown in section,

Fig. 4 is a detail section taken substantially on the line 4-4 of Fig. 3,

Fig. 5 is a detail perspective of one of 55 the hinge pins,

Fig. 6 is a detail perspective of one of the links, and

Fig. 7 is a longitudinal section through the fastener showing the same positioned 60 at a corner.

Referring to the drawing in detail, it will be seen that the numerals 5 designate the two hinge plates which are adapted to be fixed to the panel boards of the stake 65 gate in any suitable manner. The adjacent edges of these plates 5 are provided with sleeve 6. Each sleeve 6 is in two sections separated by a slot 7. The lower section of each sleeve 6 is provided with an inwardly 70 extending lug 8.

A pair of links 9 have their adjacent ends reduced as at 10 and apertured as at 11, while their outer ends are apertured as at 12. The reduced ends 10 are placed one 75 on top of the other as is indicated to advantage in Fig. 1, and a pin 13 pivots them together. The outer ends are placed in the slots 7 and the apertures 12 are in registry with the bores of the sleeve 6 and hinge pins 14 are inserted through the sleeves and apertures 12 for pivoting the links to the leaf plates 5.

As is shown to advantage in Figs. 3, 4 and 5, each hinge pin 14 is provided with 80 a suitable head 15 in order that the pin may be easily turned and removed when desired. The lower end of each pin is provided with a longitudinally extending groove 16 communicating with an annular 85 groove 17 disposed adjacent the lower end of the pin.

These grooves 16 and 17 form a kind of bayonet slot so that the pins may be inserted in the sleeves and through the aperture 12 so that the groove 16 receives the lug 8 and the pin is then pushed down until the lug is positioned in the annular groove 17 after which the pin is turned and thus is locked 90 against accidental displacement.

100 It is thought that the construction of the invention will now be clearly understood without a more detailed description. It is preferable to form the various parts which I have described of metal although any suitable material may be used. It will be apparent from the above that this fastener enables the operator, as well as the builder,

to stake the gates on any part of the truck body platform. The fastener may be used at the corners, the same as on the sides. Heretofore, fasteners in use must be placed 5 at one exact place on the wagon or truck body by the builder and also by the operator, and cannot be used except in that place. The stake gates must always be placed with the old fasteners at one precise place.

The present fastener enables the builder or operator to place the stake gate on any part of the body platform and the parts of the fastener retain said stake gate in its 15 place. In operation, the fastener permits the operator to work more rapidly in placing the stake gates in position. He is not compelled to take time to decide the exact place where each stake must be placed.

Under the old method, there had to be a 20 different fastener at the corners from that on the sides. This present fastener may be used at the corners as well as at the sides and therefore can be manufactured in larger 25 quantities and consequently cheaper than the ordinary fastener.

The various parts of the device are easy 30 to assemble and to disassemble and will prove strong and durable in use. It is apparent that the present embodiment of the invention which I have described in detail, attains all the features of advantage enumerated as desirable in the statement of the invention and the above description, and

that numerous changes in the details of construction, and in the combination and arrangement of parts may be resorted to without departing from the spirit or scope of the invention as hereinafter claimed, or sacrificing any of its advantages.

Having thus described my invention, what I claim as new is:—

1. A fastener of the class described including a pair of plates having their adjacent edges provided with sleeves, each sleeve being formed in a pair of aligned sections separated by a slot, a pair of pivoted links having their ends apertured, and hinge pins adapted to pass through the sleeves and the apertures of the links.

2. A fastener of the class described including a pair of plates having their adjacent edges provided with sleeves, each sleeve being formed in a pair of aligned sections separated by a slot, a pair of pivoted links having their ends apertured, hinge pins adapted to pass through the sleeves and the apertures of the links, the lower sections of the sleeves being provided with inwardly extending lugs, and said pins being provided with longitudinally extending slots starting from their lower ends and terminating intermediate their ends and annular grooves at the termination of the longitudinal grooves for receiving the lugs all in the 60 manner and for the purpose specified.

In testimony whereof I affix my signature.

BEN B. JOHNSTON.
